UNITED STATES PATENT OFFICE.

ELMER E. BEARD, OF OLYMPIA, WASHINGTON.

COMPOSING STICK FOR MATRICES OF TYPOGRAPHICAL MACHINES.

Application filed April 8, 1927. Serial No. 182,120.

The object of my invention is to provide a composing stick for matrices whereby a printer with a single magazine linotype is enabled to use all sizes of matrices from six 5 to forty eight point without change of magazine, so that the use of my improved stick without, in any way, interfering with the operation of the machine adds to the linotype and similar line casting type setting 10 machines all the advantages of the "Ludlow" and similar nonmagazine line casting machines.

In small plants that still have the older models of typesetting machines without the 15 universal knife block or recess mold, my stick will be found of great advantage in providing for the use of a number of up-to-date job and advertising fonts from 6 to 18 point at a minimum cost.

20 In the larger shops where they have multiple magazine machines, the range of work is limited to the number of magazines. The machines will not set letters that are very greatly extended and even with the most up 25 to date multiple magazine machines 6 or 8 fonts of matrices are all that may be carried without change of magazine. My improved stick will allow them to handle any number of fonts of large and extended matrices.

30 With my improved composing stick for matrices it is possible with the extra fonts of matrices, to do all job work and the setting of advertising on a one magazine machine. In fact, it enables the linotype to 35 double its capacity in this respect that, in addition to its own capacity, it is now able to do the work of the "Ludlow" and other nonmagazine line casting typesetting machines.

40 In the drawings:

Figure 1 is a top plan view of my improved composing stick.

Figure 2 is a similar view with some of the parts in a different position.

45 Figure 3 is a sectional view on the line 3-3, Figure 1.

Figure 4 is a sectional view on the line 4-4, Figure 2, looking in the direction of the arrows.

50 The handle of my stick consists of the base 5 and the side wall 6; the side wall extending beyond the forward end of the base as at 7 (see Figures 1 and 2), and constituting one of the end walls of the mat chamber, said end wall 7 being notched as at 8 to align with a corresponding notch in

the matrices of the linotype and similar line-casting type setting machines.

The stationary wall 9 of the mat holder is rigidly secured to the forward end of the 60 handle 5 and is also secured to the side wall 6 of the handle by means of a gusset 10. The movable rear wall 11 of the mat holder carries the end wall 12 of the holder which like the end wall 7 is notched in its upper 65 edge as at 13 in alignment with the notch 8.

A lug 14 projects rearwardly from the movable rear wall 11 to which one end of the coiled spring 15 is attached, the other end of the spring being secured to the wall 6 of 70 the handle, said spring tending to draw the movable walls 11 and 12 toward the side wall 8 of the mat holder, but this tendency is resisted by the rack bar 16 which is secured to the rear movable wall 11 and projects through and travels in a slot 17 in the rear wall 9, the movement of which is controlled by the pawl 18 which is pivoted at 19 to the flange 6 of the handle. This pawl 18 is provided with an operating handle 20. 75 A flat spring 21 is secured at one end to the handle 5, while its other end is in engagement with the pawl 18 to normally hold the pawl against the flange 6 and return it to that position after it has been operated. 80 The pawl 8 is provided with a slot 22, whereby it may be moved endwise relatively to the pivot 19. This pawl 18 is provided with a finger pull 23 to which one end of the spring 24 is attached while the other end of the 85 spring is secured to the rear wall 9 of the holder, whereby the pawl is held in operative engagement with the rack 16.

It is, of course, understood that the stationary end wall 7 is provided with a slot 25 90 through which one end of the movable rear wall 11 passes when the spring 15 pulls the end wall 12 toward the end wall 7.

A movable bottom 26 is normally positioned under the mat holder to support the 100 mats, and is provided with a stem 27 which is slidably secured to the handle 5 by means of the bolts, set screws, or rivets, 28, which operate in the elongated slots 29 formed in the handle 5, said stem 27 being provided 105 with an arm 30 that projects beyond the side edge of the handle 5 as shown in Figures 1 and 2.

The movable wall 11 is provided with a rib 31, downwardly inclined, so that the mats 110 will stand snugly in the holder when the top edge of the rear walls are below the ears

of the mat, whereby the mats may be picked from the holder by the ears as they are taken out to be distributed. This bar 31 moves through a corresponding slot in the end 5 wall 7. This bar 31 is graduated to picas and half picas so that the stick is quickly adjusted to any measure. If the machine is to set slugs 13 ems, or picas, long, it is necessary to open the side walls of the stick 10 to 13 pica ems.

When a sufficient number of mats to make a line have been placed in the holder, the operator places his thumb on the arm 23 and pulls the pawl 18 backward, thereby disengaging it from the rack 16, whereupon the spring 15 pulls the end wall 12 and the rear wall 11 toward the end wall 7 whereby the mats are firmly clamped between the end walls 7 and 12; the rear wall 11 sliding 15 through the slot 25.

The operator then places the stick in the assembler of the linotype, and presses his finger against the handle 20 to throw the end of the pawl 18 outward and to the right 20 whereupon the rack (and with it the end wall 12) are moved toward the right so that the matrices are free to drop freely into the assembler of the linotype.

Previous to this operation, however, the 30 underplate 26 has been pulled back, (to the dotted line position) by pulling on the arm 30, thus leaving the mats free to drop into the assembler when the pawl 18 has been moved to the right, opening slightly the 35 end walls or jaws 7 and 12.

As soon as the linotype has made the cast and the matrices have been transferred to the second elevator of the machine, the second elevator is stopped and the end walls 40 7 and 12 of the stick opened by pressure of thumb applied to left end of rear wall 11, toward the right, the stick is then slipped over the mats as they hang from the second elevator, and the operator again pulls 45 the arm 23 disengaging the pawl 18 from the rack 16, thus allowing the spring 15 to clamp the end walls firmly against the mats which are then slid off at the left end of the elevator.

50 The operator now moves, as above described, the end wall 12 and distributes the matrices to their various boxes in the case.

What I claim is:

55 1. A composing stick for matrices of line casting type setting machines, including a chamber for the mats, and a movable bottom for said chamber.

2. A composing stick for mats of line casting type setting machines, including an extensible chamber for the matrices, and a 60 movable bottom for said chamber.

3. A composing stick for mats of line casting machines, including an extensible chamber for the matrices, means to hold the chamber in extended position and a movable bottom for said chamber. 65

4. A composing stick for mats of line casting machines, comprising a matrix holder, having an adjustable end, means to hold said end in extended position until the matrices are set, and means to move said end to lock the matrices in the holder. 70

5. A composing stick for matrices of line casting machines, comprising a matrix holder, having adjustable ends, means to hold 75 said end in extended position until the matrices are set, and means to move said end to lock the matrices in the holder, and a movable bottom for the holder which, when moved, permits the matrices to be dropped vertically into an assembler. 80

6. A composing stick for matrices of line casting machines, comprising a matrix holder having a fixed and a movable section, a handle connected with said holder, a rack bar on the movable section of the holder, a releasable locking element on the handle engaging said rack bar, means to move the movable section toward the fixed section when said pawl is released from said rack. 85 90

7. A composing stick for matrices of line casting machines, comprising matrix holder having a fixed and a movable section, a handle connected with said holder, a rack bar on the movable section of the holder, a releasable locking element on the handle engaging said rack bar, means to move the movable section toward the fixed section when said pawl is released from said rack, a bottom for the holder, and means to remove said bottom from beneath the holder. 95 100

8. A composing stick for mats of line casting machines, comprising a handle, a mat holder, one end wall of which is movable toward the other, a rack bar connected with the movable end wall, a tension spring between the movable end wall and the handle, a pawl mounted on the handle, and means to operate this pawl, a movable bottom for the holder, and means to move said bottom from beneath the holder. 105 110

In testimony whereof I affix my signature.

ELMER E. BEARD.
